INTERNAL COMBUSTION ENGINE

James S. Frazer, Earleville, Md.

Application August 25, 1937, Serial No. 160,898

15 Claims. (Cl. 123—51)

This invention relates to improvements in internal combustion engines, capable of general use but particularly intended for the propulsion of aircraft, and has generally in view to provide an engine which, for any given horsepower, is of exceptionally light weight; which is of simple, sturdy construction and of relatively low production, operation and maintenance cost; which is so designed that it may be disassembled quickly and easily for the repair or replacement of parts, and equally as readily reassembled; which possesses long life and is thoroughly reliable and highly efficient in operation; which presents a comparatively small frontal area; and which is of such shape that it may readily be mounted within the wing structure of an aircraft, thereby totally to eliminate, or substantially totally to eliminate, resistance to flight of the aircraft insofar as the engine is concerned.

Preferably the present engine is of the opposed piston, dual crank shaft type operating on the two stroke cycle, mechanical fuel injection, internal vaporizing, high pressure ignition principle, whereby valve, valve mechanism and ignition troubles, such as have heretofore been experienced in connection with engines having valves and electrical ignition systems, are eliminated and reliability is correspondingly increased. However, the engine may be constructed to operate on the four stroke cycle principle, and whether constructed to operate on this or the two stroke cycle principle, may be designed to employ either solid or carbureted fuel, and may be equipped with an electrical ignition system. In any event, a crank case is provided at each end of the cylinder, or the series of cylinders, as the case may be, and said crank cases are separate from the interposed cylinder or cylinders and are connected together by tie rods, whereby the engine may be quickly and easily assembled and disassembled. In this connection, a special object of the invention is to provide novel, practical means for maintaining the crank cases at all times spaced apart a single, definite amount regardless of longitudinal expansion and contraction of the cylinder or cylinders, or, conversely, to provide a connection between the crank cases permitting longitudinal expansion and contraction of the interposed cylinder or cylinders without affecting the definite spaced apart relationship of the crank cases, whereby longitudinal expansion or contraction of the cylinder or cylinders does not affect the gear connection which is provided between the crank shafts journaled in the crank cases, nor seriously affect the opera-

tive relationship between other cooperating parts, such as the fuel pumps and their operating shafts, which are, or may be, carried by or connected with the cylinder or cylinders and one or both of the crank cases, respectively.

Another special object of the invention, in the case of an engine of the character mentioned and constructed to operate on the two stroke cycle principle, is to provide a scavenging and combustion air inlet port which is so designed as not to impart turbulence to the air initially admitted to the cylinder, but to impart turbulence to the air last admitted to the cylinder, so that the initially admitted air does not mix readily with the burnt gases contained within the cylinder, but serves as an effective fluid piston for the expulsion of the burnt gases, and so that the air last admitted mixes readily with the fresh fuel charge and materially assists its combustion.

Another special object of the invention is to provide between the dual crank shafts of the engine a novel gear connection which is contained substantially entirely within the limits of the frontal area of the crank cases and the cylinder or cylinders.

Another special object of the invention is to provide a novel sectional crank shaft construction to permit the use of anti-friction ball or roller bearings for the crank shafts and to permit the number of engine cylinders or units to be readily increased or decreased.

With the foregoing and other objects in view, which will become more fully apparent as the nature of the invention is better understood, the same consists in the novel features of construction, combination and arrangement of parts as will be hereinafter more fully described, illustrated in the accompanying drawings and defined in the appended claims.

In the drawings, wherein like characters of reference denote corresponding parts in the different views:

Figure 1 is a front elevation of an engine constructed in accordance with one practical embodiment of the invention.

Figure 2 is a central longitudinal section through the engine.

Figure 3 is a longitudinal section at right angles to Fig. 2.

Figure 4 is a longitudinal section taken approximately on the line 4—4 of Fig. 2.

Figure 5 is a detail sectional view showing the air inlet ports of one of the cylinders.

Figures 6 and 7 are detail cross sections on the lines 6—6 and 7—7, respectively, of Fig. 5.

Figure 8 is a transverse section taken approximately on the line 8—8 of Fig. 2.

Figures 9 and 10 are cross sections through the exhaust and the intake manifolds, respectively, of one of the cylinders.

Figure 11 is a detail longitudinal sectional view through one of the sectional crank shafts 10 of the engine.

Figure 12 is a detail cross section showing the splined connection between the separate sections of one of the crank shafts.

Figure 13 is an enlarged longitudinal section 15 through one of the pairs of the fuel injection pumps and their actuating and stroke regulating means.

Figure 14 is a detail sectional view of one of the fuel injection nozzles.

Figure 15 is a sectional view showing a power take-off gearing arrangement for coaxial, oppositely rotating propeller shafts; and

Figure 16 is a fragmentary sectional view 25 through one of the cylinders showing spiral air inlet ports.

As will be understood, the present engine may comprise only a single cylinder or a plurality of cylinders. It will also be understood that the cylinders may be finned for air cooling or jacked 30 for liquid cooling, and that the engine may be installed to operate in a vertical, horizontal or inclined position. In the present instance the engine is illustrated as being of the multiple cylinder type comprising any desired number of 35 cylinders 10 which, in accordance with the invention, are disposed in a common plane in side to side, spaced, parallel relationship.

Each cylinder is open at each end, and at each 40 end of the series of cylinders is a crank case 11 having in its inner wall 12 a series of openings in which the adjacent ends of the cylinders are neatly fitted wheret; the cylinders are held effectively against any lateral movement relative to each other. The end portions of said cylinders are, however, longitudinally slidable relative 45 to the crank cases through said openings. To prevent leakage of oil from the crank cases around the end portions of the cylinders, the latter preferably are embraced by sealing rings 12' of rubber or other suitable material which 50 may be seated in grooves in the walls surrounding the openings in the crank cases through which the end portions of the cylinders extend.

In order to maintain the two crank cases 11, 11 in definite, spaced apart relationship, a number 55 of spacing elements in the form of elongated spools 13 are interposed between the adjacent or inner walls 12, 12 of said crank cases. On the other hand, in order to clamp the two crank cases against the ends of the spools 13, thus to tie said crank cases firmly together, tie rods 14 are extended through said spools, through 60 crank shaft bearing housings 15 which are cast integrally with the crank cases within the latter, through bearing caps 31, and at their ends are provided with nuts 16 cooperating with said bearing caps.

Between medial portions of the cylinders 10 and the spools 13 are suitable interengaging formations 70 whereby the cylinders are held against shifting longitudinally relative to the crank cases 11. In the present instance these formations comprise fingers 17 on the spools 13 engaged between pairs of lugs 18 on the cylinders, and 75 since any longitudinal expansion or contraction

of the cylinders develops in opposite directions from the middle portions thereof where said formations are located, it follows that while the cylinders thus are held effectively against any longitudinal shifting movement bodily relative to the crank cases, the end portions of said cylinders are, nevertheless, free to move longitudinally relative to the crank cases under expansion and contraction.

Journalized in suitable bearings mounted in the bearing housings 15 of the respective crank cases are crank shafts 19, 19 each having a plurality of cranks, one related to each cylinder, while within each cylinder is a pair of pistons 20, 20 which are connected by rods 21, 21 to the related cranks of the respective crank shafts, the crank shafts being suitably geared together, and related cranks being so disposed, that the two pistons within each cylinder move simultaneously inwardly during compression periods of the engine and simultaneously outwardly during firing periods of the engine.

In the present instance the gearing connecting the two crank shafts 19, 19 comprises a bevel gear 22 on each crank shaft and a shaft 23 carrying a pair of bevel pinions 24 meshing, respectively, with the gears 22, 22. This gearing is disposed at one end of the series of cylinders 10 in the plane of said cylinders, and a feature of said gearing is that it is confined substantially within the frontal area of the engine, which is of importance in reducing air resistance if the engine is used in an aircraft. The pairs of bevel gears 22, 24 are enclosed within housings 25 formed with or fastened to the crank cases 11, and the shaft 23 is journaled in suitable bearings, preferably of the anti-friction ball or roller type, mounted in said housings 25. In one of the housings 25 is suitably journaled a power take-off or propeller shaft 26 having a bevel gear 27 meshing with the related bevel pinion 24 on the shaft 23, or, alternatively, with a separate bevel gear on the shaft 23, as may be desired. In this connection the gear 27 obviously may be of any desired diameter to afford any desired reduced speed ratio between the propeller shaft and the engine crank shafts.

It is desirable that all, or at least some, of the main bearings of the crank shafts 19, 19 be of the antifriction ball or roller type. In the case of an ordinary, one-piece crank shaft it obviously is not possible to employ a ball or roller bearing between adjacent crank portions of the shaft because of the annularly continuous nature of the bearing and because it can be placed on a shaft, or a shaft can be inserted therein, only by relative endwise movement of the bearing and the shaft, which, in the case of a one-piece crank shaft, is prevented by the cranks. Accordingly, the present crank shafts 19, 19, preferably are formed in separate sections each comprising one or more cranks, and said sections are formed at adjacent ends with interfitting, splined male and female portions 28 and 29, respectively, as illustrated in Figs. 2, 11 and 12 of the drawings. Thus, in the assembly of the present engine it obviously is an easy matter to employ anti-friction ball or roller main bearings 30 between adjacent cranks of the shafts because said bearings may be engaged over the hollow or female end portions of the crank sections prior to inserting the male portions of adjacent crank sections in said female portions. Another advantage of this sectional crank shaft construction is that a given crank shaft comprising any de-

sired number of cranks may be assembled from the present crank shaft sections, thus avoiding the necessity of manufacturing crank shafts embodying different numbers of cranks for use in engines having different numbers of cylinders, as would be necessary if the crank shafts were of one-piece construction. In this connection, by having twenty-four evenly spaced splines between each two crank shaft sections it obviously is possible to properly angularly space the respective cranks to form shafts for two, three, four, six or eight cylinder two-stroke engines.

While any or all of the crank shaft main bearings may be of either the usual journal type or of the anti-friction ball or roller type, it is preferred that said two types of bearings be alternated along the length of each crank, as illustrated in Figs. 2 and 9. In any event, the bearing housings 15 preferably are recessed as illustrated in Figs. 4 and 9 to receive and hold the removable half portions or caps 31 of said bearings. The ends of the caps 31 are faced to fit between corresponding facings on the cheeks 15a formed by recessing the bearing housings 15, and 25 said bearing housings, including the cheeks 15a, are connected with the side walls of the crank cases by webs 32 disposed forwardly and rearwardly well beyond the crank shaft center line. Moreover, the related tie rods 14 preferably are 30 employed to secure said bearing half-portions in said recesses, thus simplifying the engine construction and at the same time assuring firm, rigid support of the crank shafts within the crank cases, especially since the bearing housings, which 35 extend from the inner walls 12 of the crank cases, are reinforced by transverse tie rods 33 extending between the side walls of the crank cases preferably adjacent to the crank shaft main bearings. These tie rods serve not only to relieve the bolts 40 of bending strains incident to explosion and compression loads, but also to prevent any minute flexing of the back portions of the journal bearings, which flexing heretofore has been found to constitute a greater cause of bearing failure 45 than wear or faulty lubrication. In the case of such of the main bearings as may be of the ordinary journal type permitting the tie rods to be located closely adjacent to the shaft journals, said tie rods may extend from top to bottom of 50 the crank cases normal to the cylinder axes. On the other hand, in the case of such of the main bearings as may be of the ball or roller type, the tie rods preferably are formed in two parts which meet in lugs resting on or integral with the bearing caps 31 and from said lugs are inclined 55 inwardly so that their outer ends cooperate with the top and bottom walls of the crank cases at points more nearly overlying and underlying the crank shaft journals. By exerting inward pressure on the cheeks 15a of the bearing housings and thereby holding the facings on the inner sides of said cheeks firmly engaged with the facings on the ends of the bearing caps, any flexing of the back portions of the journal bearings is 60 effectively avoided.

Further regarding the crank shafts 19, 19, these preferably are of hollow construction as illustrated in Fig. 9 for best heat treatment in their manufacture and to afford a convenient means of conducting lubricant to the crank shaft main bearings, the connecting rod bearings and the piston wrist pins. The ends of the hollow main and crank portions of the shafts are closed by pairs of disks 34 connected together and held 65 in place by bolts 35, and oil is supplied to said

hollow shaft portions in any desired manner. Ducts 36 connect the respective hollow portions and other ducts lead from said portions to the main and connecting rod bearings and through the connecting rods to the wrist pins.

As aforesaid, the engine is of the two-stroke cycle, mechanical fuel injection type in which air is highly compressed between related pistons upon inward movement of the same and in which explosions are produced for driving the pistons outwardly by the injection of fuel under high pressure into the combustion spaces between the pistons when the latter are in, or substantially are in, their innermost positions. Near one end of each cylinder is an annular series of ports 37 which are uncovered by the related piston for the admission of air to the cylinder when said piston is in its outermost position, while near the other end of each cylinder, preferably at both the top and the bottom thereof, are ports 38 which are uncovered by the other piston for the escape of burnt gases from the cylinder when the latter piston is in its outermost position.

In order to assure the supply of a sufficient volume of scavenging and combustion air to each cylinder upon completion of outward movement of the related pair of pistons 20, 20 each crank case 11 has mounted thereon, outwardly of its crank shaft and in alignment with each cylinder 10, an air cylinder 39. In other words, there 30 are two air cylinders 39, one at each end of the engine, related to each power cylinder 10, and from each related pair of these air cylinders air conduits 40 lead to manifolds or receivers 40' from which branch conduits 40a lead to the ports 37 of the related power cylinder. Preferably the conduit from one air cylinder leads to the ports at one side of the middle of the cylinder and the conduit from the other air cylinder leads to the ports at the other side of the middle of the cylinder 40 to assure a substantially uniform supply of air to the cylinder circumferentially thereof.

Within each air cylinder 39 is a piston 41 which is connected by a rod 42 to the related connecting rod 21 so that as each piston 20 moves outwardly in its power cylinder 10 the related piston 41 moves outwardly in its related air cylinder, thereby compressing air in the latter cylinder and in the conduit 40 so that when the air ports 37 are uncovered by the related piston 10, a charge 50 of scavenging and combustion air under pressure rushes into the cylinder 10. In this connection, any suitable valve means may be provided to admit a fresh charge of air to each air cylinder 39 upon subsequent inward movement of 55 the related piston 41. Also in this connection, a feature of the invention resides in forming the ports 37 of each cylinder 10 as shown in Figs. 5 to 7 of the drawings, so that the air initially entering each cylinder 10 does not have turbulence 60 imparted thereto and therefore does not mix readily with the burnt gases contained in said cylinders, but serves as a fluid piston for the expulsion of the burnt gases, and so that turbulence is imparted to the air last admitted to each 65 cylinder, whereby its thorough admixture with the fresh fuel charge is assured. In other words, that portion 43 of each air port 37 which first is uncovered by the related piston has its side walls disposed radially, or parallel to the medial, radial plane of the port so that the air first entering the cylinder 10 does so in a radial direction; whereas, that portion 44 of each port 37 which lastly is uncovered by the related piston, has its side walls inclined to the medial, radial plane of 75

the port, or, in other words, disposed tangentially to the cylinder 10, so that the air lastly entering the cylinder does so tangentially and therefore in a swirling or turbulent manner. The inclination of the side walls of the portions 44 of the ports 37 is such, as may be determined by experiments, to give the best swirling or turbulent effect to the air lastly entering the cylinder.

Preferably the cranks of one of the crank shafts are given a suitable lead over the cranks of the other crank shaft, as illustrated in Fig. 3, so that the exhaust ports 38 of each cylinder are uncovered sufficiently in advance of uncovering of the air inlet ports 37 to permit the pressure of the burned gases in the cylinder to become equal to, or lower than, the pressure of the scavenging air which subsequently enters the ports 37. Thereby thorough scavenging is effected. Moreover, since the exhaust ports are closed in advance of the intake ports there is obtained in each cylinder a supercharge of air.

While fuel may be injected into the cylinders 10 in any desired manner, it is preferred that the same be injected in a plurality of separate jets at points spaced circumferentially, of each cylinder, thus to assure a thorough intermixiture of the fuel and air within the very short period of time allowed for this purpose. There may be a single pump or fuel supply conduit for each cylinder communicating with the latter through a plurality of circumferentially spaced openings, or there may be a plurality of fuel pumps or supply pipes, one individual to each nozzle or opening. In the present instance each cylinder 10 is illustrated as being equipped with two fuel pumps, designated generally as 45, each communicating with the cylinder through a pair of nozzles, designated generally as 46, spaced ninety degrees apart.

The fuel pumps 45 may be of any suitable type and may be actuated in any suitable manner. In the present instance the pumps of each pair are located directly above and below the related cylinder, respectively, and each pump (see Fig. 13) comprises a pair of aligned cylinders 47, 47 each provided with a reciprocable piston or plunger 48. The cylinders 47, 47 are mounted within housings 49 which are connected together in end to end relationship by a fitting 50, and from the fitting 50 pipes 51 lead to the related pair of nozzles 46, the said pipes 51 being in communication with the inner ends of the pump cylinders through, preferably, dual check valve controlled ports as illustrated in Fig. 13, whereby any possibility of engine cylinder pressures affecting the fuel pumps is avoided. In this connection, and if desired, another check valve 52 may be provided in each pipe 51 adjacent to the related fuel nozzle 46.

Fuel supply lines are designated as 53 and are connected by branch pipes 54 with ports 55 at the inner ends of the fuel pump cylinders, the said ports 55 being disposed to be uncovered by the pump pistons 48 as the latter move outwardly to admit charges of fuel to the pump cylinders, and to be covered by the pump pistons as the latter move inwardly, whereby the admitted fuel charges are forced to the related pair of fuel nozzles.

The pump pistons are movable outwardly by suitable springs 56 and are movable inwardly by suitable cams on cam shafts 57 mounted in the crank cases 11 and driven in properly timed relationship to, and from, the engine crank shafts through suitable gearing 58, the arrangement of

said cam shafts and cams being such, as shown, that the pistons of each pump are driven inward alternately.

Between each pump piston and its related cam is a mechanism of known type for varying the amount of fuel injected by the pump by regulating the piston stroke while maintaining a constant lead and duration of the injection period for all engine loads. As best illustrated in Fig. 13, each mechanism comprises a cam follower 59 in the form of an arm pivoted at one end within the related crank case 11; a guide sleeve 60 mounted on the related crank case in alignment with the related pump cylinder and having reciprocable therein a member 61 connected to the related pump piston; and a link 62 pivotally engaged at one end with the inner end of the member 61 and slidably engaged at its other end with the related cam follower arm 59. Obviously, by moving the last mentioned end of the link 62 toward the pivot of the arm 59 the stroke of the related pump piston is reduced. On the other hand, by moving the last mentioned end of said link away from the pivot of the arm 59 the stroke of the pump piston obviously is increased.

Novel means are provided in the present instance for adjusting the links 62. For each link said means comprises a screw 63 mounted in the related crank case; a link 64 connecting said screw with the link 62 so that by longitudinal movement of the screw 63 the end of the link 62 in engagement with the cam follower arm 59 may be moved toward or from the pivot of said arm; and a gear 65 mounted for rotation and held against longitudinal movement relative to the crank case and having the screw 63 threaded therethrough. Thus, by rotating the gear 65 the screw 63 may be longitudinally adjusted to move the end of the link 62 adjacent to the cam follower arm 59 toward or from the pivot of said arm. Related to each set of corresponding gears 65 is a shaft 66 having thereon gears 67 one in mesh with each of the gears 65 of the set, so that by rotatably adjusting any given shaft 66 all of the gears 65 of the related set are rotated in unison to impart corresponding adjustments to the related set of links 62.

The nozzles 46 are of novel construction and are designed to remain closed against engine cylinder pressures and to be opened by pressure of the fuel supplied thereto by the fuel pumps 45. As illustrated in detail in Fig. 14 of the drawings, each nozzle 46 comprises a body 68 having an axial bore 69 closed at its outer end by a plug 70 and opening at its inner end into a fuel chamber 71 within the inner end portion of said body; a small orifice 72 for discharge of fuel from said chamber 71 through the inner end of the body 68; a piston 73 within the bore 69 having a reduced end to enter and close the orifice 72; a coil spring 74 interposed between the outer end of the piston 73 and the plug 70 and tending constantly to move said piston inwardly to cause the reduced inner end of the piston to close the orifice 72; and a duct 75 leading to the chamber 71 from the fuel supply pipe 51 connected with the body 68.

The body 68 is attached to a cylinder boss 76 and the orifice 72 at the inner end of said body is disposed to discharge into the cylinder. Therefore, the inner end of the piston 73 is exposed to engine cylinder pressures. Due, however, to the small area of the reduced inner end of said piston 73 the highest pressures developed within

the engine cylinder are incapable of moving said piston outwardly against the force of the spring 74. On the other hand, due to the relatively large area of the inner end portion of the piston 73 which is exposed to pressure of liquid within the chamber 71, said piston readily is moved outwardly against the spring 74 to open the orifice 72 and thereby permit injection of fuel into the engine cylinder under the fuel pressure generated by the fuel pump.

As illustrated in Fig. 9 of the drawings, the exhaust conduits 77 leading from the exhaust ports 38 at the top and at the bottom of each cylinder 10 to upper and lower exhaust manifolds 78, are divided to provide spaces to accommodate the fuel pump mechanisms. The air conduits 40 leading from the air cylinders 39 to the air inlet ports 37 may be similarly divided. Preferably, however, the two air conduits from the two air cylinders 39 related to each power cylinder 10 extend, respectively, approximately one-half the distance around the power cylinder, as illustrated in Fig. 10, to provide the spaces necessary to accommodate the fuel pump mechanisms. Moreover, by this arrangement the air from the two air cylinders is delivered uniformly to the power cylinder at opposite sides thereof.

In Fig. 15 of the drawings is illustrated a practical power take-off gearing to be used in lieu of the gearing shown in Fig. 2 when it is desired to drive coaxial propeller shafts in opposite directions. As in the case of the gearing illustrated in Fig. 2, the crank shaft 19 carries a bevel gear 22 which meshes with a bevel gear 24 on the shaft 23. However, instead of the bevel gear 27 on the propeller shaft 26 meshing with the bevel gear 24 as in the Fig. 2 arrangement, said bevel gear 27 meshes with a separate bevel gear 79 on the shaft 23 and a third bevel gear 80 on said shaft 23 meshes with a bevel gear 81 on a second propeller shaft 82 which is hollow and telescoped over the first mentioned propeller shaft 26. The gears 79 and 80 face oppositely. Therefore, the two propeller shafts 26 and 82 are driven in opposite directions either at equal speeds or at different speeds, depending upon the relative diameters of the gears 27, 79 and 80, 81.

From the foregoing description considered in connection with the accompanying drawings it is believed that the construction, operation and advantages of the present engine will be clearly understood. It is desired to emphasize, however, the simplicity of the construction; the fact that the cylinders are free to move at their ends relative to the crank case without affecting the spaced apart relationship of the crank cases or the gearing connecting the crank shafts, or the connections between the fuel pumps and their actuating means, the explosion loads being taken through bolts and the crank case walls being under compression, thus permitting the use of a higher compression ratio and a more efficient combustion cycle than heretofore has been considered practicable; the provision for utilizing anti-friction crank shaft main bearings; the provision for building up crank shafts having different numbers of cranks from the crank shaft sections; the provision for supplying air to the cylinders in the manner described; the novel gearing connecting the crank shafts, and the relatively small frontal area of the engine permitting it readily to be mounted in a horizontal position within the wing structure of an aircraft. It is further desired to point out that while only a single structural embodiment of the invention has been ill-

lustrated and described, the features comprising the invention may be embodied, entirely or in part, in engines having different structural embodiments, within the spirit and the scope of the invention as defined in the appended claims.

Fig. 16 of the drawings illustrates that the scavenging and combustion air ports may be in the form of a number of spaced, narrow, helical slots, designated as 37a, to afford relatively large port areas within given distances longitudinally of the cylinders. As will be understood, these helical slots 37a may have the portions thereof corresponding to the portions 43 and 44 of the ports 37, formed as described in connection with said portions 43 and 44 of said ports 37.

I claim:

1. An internal combustion engine of the opposed piston type comprising a cylinder, a crank case at each end of said cylinder, spacing elements between said crank cases, and tie rods clamping said crank cases against the ends of said spacing elements, the ends of the cylinder being freely movable longitudinally relative to the crank cases.

2. An internal combustion engine of the opposed piston type comprising a cylinder, a crank case at each end of said cylinder, spacing elements between said crank cases, tie rods clamping said crank cases against the ends of said spacing elements, the ends of the cylinder being freely movable longitudinally relative to the crank cases, and means between at least one of said spacing elements and a medial portion of the cylinder holding the medial portion of the cylinder against longitudinal movement relative to the spacing elements and the crank cases.

3. An internal combustion engine of the opposed piston type comprising a cylinder, a crank case at each end of said cylinder, the ends of the cylinder being freely movable longitudinally relative to the crank cases, means independent of the cylinder holding the crank cases in a definite spaced apart relationship, and a connection between a medial portion of the cylinder and said means holding the medial portion of the cylinder against longitudinal movement relative to said means and the crank cases.

4. An internal combustion engine of the opposed piston type comprising a cylinder, a crank case at each end of said cylinder, spacing elements between said crank cases, tie rods clamping said crank cases against the ends of said spacing elements, the ends of the cylinder being freely movable longitudinally relative to the crank cases, and interfitting formations on medial portions of the cylinder and said spacing elements, respectively, holding the medial portion of the cylinder against longitudinal movement relative to said spacing elements and the crank cases.

5. An internal combustion engine of the opposed piston type comprising a cylinder, a crank case at each end of said cylinder, the ends of the cylinder fitting into said crank cases and being freely movable longitudinally relative thereto, tie rods and means cooperating therewith holding the crank cases in a definite spaced apart relationship independently of the cylinder, and crank shaft half-bearings in said crank cases, the tie rods extending through said half-bearings and serving to hold them operatively positioned within said crank cases.

6. An internal combustion engine of the opposed piston type comprising a cylinder, a crank case at each end of said cylinder, crank shafts within said crank cases, a pair of pistons within

said cylinder connected to said crank shafts, respectively, crank shaft main bearings including caps, tie rods connecting the crank cases together and holding the crank shaft main bearing caps in operative positions, and other tie rods extending transversely relative to said first mentioned tie rods between opposite side walls of each crank case adjacent to said crank shaft main bearings, there being integral connecting formations between the main bearings and the side walls of the crank cases.

7. In an internal combustion engine, a cylinder, a crank case, a crank shaft within said crank case, main bearings for said crank shaft, a piston within said cylinder connected to said crank shaft, and tie rods connecting together opposite side walls of said crank case, said tie rods being located adjacent to said main bearings at the sides thereof remote from the cylinder and extending transversely relatively to the axes of the cylinder, and the crank shaft, there being integral web connections between the main bearings and the crank case side walls.

8. In an internal combustion engine of the opposed piston type, a cylinder, a crank case at each end of said cylinder, a crank shaft within each crank case, main bearings within each crank case for the crank shaft therein, tie rods connecting the crank cases together and extending through related main bearings in the respective crank cases, and other tie rods connecting together opposite side walls of each crank case, said last mentioned tie rods being located adjacent to said main bearings at the sides thereof remote from the cylinder and extending transversely relative to the axes of the cylinder and the crank shaft, there being integral web connections between the main bearings and the crank case side walls.

40 9. In an internal combustion engine of the opposed piston type, a cylinder, a crank case at each end of said cylinder, a fuel pump mechanism adjacent to said cylinder, and an exhaust conduit extending from said cylinder and divided to extend around said fuel pump mechanism.

10. An internal combustion engine of the opposed piston type comprising a cylinder, a crank case at each end of said cylinder, spacing means between said crank cases, means clamping said crank cases against said spacing means, the ends of the cylinder being freely movable longitudinally relative to the crank cases, and means holding the medial portion of the cylinder against longitudinal movement relative to said spacing means.

55 11. An internal combustion engine of the op-

posed piston type comprising a cylinder, a crank case at each end of said cylinder, spacing means between said crank cases, means clamping said crank cases against said spacing means and holding the latter operatively positioned between the crank cases, the ends of the cylinder being freely movable longitudinally relative to the crank cases, and means holding the medial portion of the cylinder against longitudinal movement relative to said spacing means.

10 12. An internal combustion engine of the opposed piston type comprising a cylinder, a crank case at each end of said cylinder, spacing means between said crank cases, means clamping said crank cases against said spacing means, the ends of the cylinder extending into the crank case and being freely movable longitudinally relative thereto, and means holding the medial portion of the cylinder against longitudinal movement relative to said spacing means.

15 13. An internal combustion engine of the opposed cylinder type comprising a cylinder, a crank case at each end of said cylinder, spacing elements between said crank cases, tie rods clamping said crank cases against the ends of said spacing elements and holding the latter operatively positioned between the crank cases, the ends of the cylinder extending into the crank cases and being freely movable longitudinally relative thereto, and means holding the medial portion of the cylinder against longitudinal movement relative to said spacing elements.

20 14. An internal combustion engine of the opposed piston type comprising a cylinder, a crank case at each end of said cylinder, spacing means between said crank cases, means clamping said crank cases against said spacing means, the ends of the cylinder being freely movable longitudinally relative to the crank cases, and means between the cylinder and said spacing means holding the medial portion of the cylinder against longitudinal movement relative to said spacing means.

25 15. An internal combustion engine of the opposed cylinder type comprising a cylinder, a crank case at each end of said cylinder, spacing means between said crank cases, tie rods extending through said spacing means and clamping said crank cases against said spacing means, the ends of the cylinder extending into the crank cases and being freely movable longitudinally relative thereto, and means holding the medial portion of the cylinder against longitudinal movement relative to said spacing means.
